UNITED STATES PATENT OFFICE.

WILLIAM SPALCKHAVER, OF NEW YORK, N. Y., ASSIGNOR, BY MESNE ASSIGNMENTS,
TO E. HOE AND CO., OF NEW YORK, N. Y., A CORPORATION OF NEW YORK.

PRINTING-MACHINE.

1,109,152.

Specification of Letters Patent. Patented Sept. 1, 1914.

Application filed June 26, 1906. Serial No. 323,418.

To all whom it may concern:

Be it known that I, WILLIAM SPALCKHAVER, a citizen of the United States, residing at New York, county of Kings, and

5 State of New York, have invented certain new and useful Improvements in Printing-Machines, fully described and represented in the following specification and the accompanying drawings, forming a part of the

10 same.

This invention relates to certain improvements in printing machines of the kind known as straight line machines in which the cylinders of the printing couples are

15 parallel and arranged in superposed decks, the webs being led in straight lines through the decks.

Multi-deck machines of the class referred to have been heretofore provided with

20 means by which the couples of the top deck could be driven at varying speeds, for the purpose of varying the number of sheets in the product. Such machines have also been provided with extra cylinders for the

25 purpose of applying color to the product. When color is to be applied to a product, however, publishers insist that the construction of the machine be such that the color pages may be made the outside pages of a

30 folded product, if desired. For this reason, it is regarded as necessary that the extra color cylinder when employed form a part of a deck which runs at full speed, the variation in the size of the product being always

35 formed by varying the number of the inner sheets or by making some of the inner sheets half width. Inasmuch as in the machines heretofore constructed, the full speed decks have been the lower decks, considerable diffi-

40 culty has been experienced in designing machines to make the necessary space for the color cylinders, especially if more than one cylinder is to be added, without unduly increasing the size of the machine. Further,

45 it frequently happens that the purchaser of a machine not originally designed for color or designed possibly for only a single color, desires to have the capacity of the machine increased by the addition of either a color

50 cylinder or additional cylinders of this description. As these cylinders must be made a part of a full speed deck, it has been here-

tofore necessary to practically reconstruct the machines in order to obtain the space of the color cylinders.

65

This invention has for its object the production of an improved printing machine of the straight line type which shall contain a full speed deck and a deck or decks capable of running at varying speeds, the full speed deck being so arranged as to facilitate the addition of color cylinders thereto.

Referring to the drawings, Figure 1 illustrates diagrammatically, in side elevation, a two deck machine constructed in accordance with the invention.

65

Fig. 2 represents in diagrammatic side elevation a three deck machine constructed in accordance with the invention.

70

Fig. 3 represents in diagrammatic side elevation the machine illustrated in Fig. 2 arranged to produce a different product.

75

Fig. 4 is an end elevation of the driving gearing for the machine illustrated in Fig. 1.

Fig. 5 is an end elevation of the driving 75 gearing for the machine illustrated in Figs. 2 and 3.

Machines constructed in accordance with the invention will be provided with a plurality of decks, each including couples by which a web may be printed and perfected. The number of decks employed may be varied according to the requirements of the work which is to be accomplished by the machine. In the construction shown in Fig. 1, a two deck machine is illustrated, the first printing cylinder of the upper or top deck being marked 1 and the impression cylinder cooperating therewith, 2. The perfecting printing cylinder is marked 3 and its cooperating impression cylinder is marked 4.

80

The cylinders derive their ink from inking apparatus of the usual type as 5, 6. The particular machine illustrated includes as a part of the upper deck a color printing cylinder 7, deriving its ink from an inking apparatus indicated at 8. In machines constructed in accordance with the invention, the upper deck will be driven at full speed. While this may be effected in various ways, 100 in the particular construction illustrated, there is employed a main power shaft 9 (see Fig. 4) which is provided with a driving gear 10. This driving gear, through inter-

85

90

95

mediates 11, 12 and 13, drives gear 14 which is secured to a countershaft 15 extending across the machine. This shaft 15 has a driving gear 16 thereon which meshes with a gear 17 on the shaft 18 of the cylinder 2. It will be understood, of course, that the power for driving the cylinders 1, 4, 3 and 7, when the cylinder 7 is employed, will be derived through intermeshing gears of the ordinary type, which construction being well-known is not illustrated. The deck just described prints on a web W derived from a suitably mounted web roll, indicated at 19.

The lower deck of the machine illustrated in Fig. 1 comprises printing cylinders 20, 21 and impression cylinders 22, 23. It may be remarked, as is characteristic of the type of machine to which this improvement relates, all the cylinders are parallel and the webs 20 are led in a straight line through the couples which are to print upon them. The cylinders 20, 21 of this lower deck receive their ink from inking apparatus indicated at 24 and 25.

The lower deck of the machine illustrated in Fig. 1 is arranged to be run at varying speeds. While this may be effected in various ways, in the construction illustrated, the shaft 9 is provided with a pair of change gears 26, 27 and there is also provided a short countershaft which is provided with a gear 28 and with a driving gear 29. This driving gear 29 meshes with a gear 30 on the shaft 31 of the impression cylinder 23. As is the case with the top deck, the other cylinders forming the remainder of the couples of this deck, are driven from the cylinder 23 through the usual intermeshing gears.

The web on which the cylinders of the lower deck print is indicated at W', this web being derived from a suitably mounted web roll indicated at 32. If it be desired to run the lower deck at half speed, so as to cause the cylinders to produce one half the product produced by the full speed top deck, the gearing is arranged as indicated in Fig. 4; that is to say, the gear 26 meshes with the gear 28 which gear drives the gear 29 through the shaft common to both these gears. The gear 29 drives the cylinder 23 through the gear 30. The teeth of the gear 26 are so proportioned to the teeth in the gear 28 as to cause this gear to run at one half the speed of the shaft 9, so that the cylinder 23 runs at one half the speed of this shaft. The gearing for driving the cylinder 2, however, is so arranged that this cylinder runs at the speed of the shaft. If it be desired to run the lower deck at full speed, the gear 26 is slipped out of mesh with the gear 28 and the gear 27 is brought directly in mesh with gear 29. The gears 27 and 29 have the same number of teeth so that with this arrangement the cylinder 23 runs at the speed of the shaft 9.

The machine illustrated in Figs. 2 and 3 is generally similar to that described, except that it contains an additional deck and that the color cylinder is omitted. The printing cylinders of the top deck are marked 33, 34 and the impression cylinders 35, 36. The printing cylinders of the middle deck are marked 37, 38, and the impression cylinders 39 and 40. The printing cylinders of the lower deck are marked 40, 41 and the impression cylinders 42, 43. The web runs and inking mechanisms will be understood without description. In this machine, as in the former machine, the top deck is driven at full speed from a power shaft, indicated at 44, this shaft having a driving gear 45 mounted thereon. This gear 45 meshes with a gear 46 which, by means of intermediates 47, 48, drives a gear 49. This gear 49, by means of intermediates 50, 51, drives a gear 52. This gear 52 is mounted on a countershaft 53 which by means of a gear 54 drives a gear 55 on the shaft 56 of the impression cylinder 36, the other cylinder of this deck being driven by suitable gearing from this cylinder. The gear 49 is fast on a shaft 57 which is provided with change gears 58, 59. These gears 58, 59 are on the same hub and may be taken off the shaft and their positions reversed. The gear 58, when it is employed, meshes with an intermediate 60 mounted on a stud 61 on the frame. This intermediate meshes with a gear 62 on the shaft 63 of the cylinder 40. With this arrangement, the cylinder 40 will run at half the speed of the cylinder 36. If it be desired to run this cylinder at full speed, the intermediate 60 is removed and the position of the gears 58, 59 is reversed, in which case the gear 59 meshes with a gear 64 on the shaft 65 of the cylinder 39. The lower deck is driven by change gears 66, 67 which operate with gears 68, 69, the gear 69 meshing with a gear 70 on the shaft 71 of the cylinder 43.

A collecting mechanism of suitable construction may be employed, in machines constructed in accordance with the invention, in order to still further vary the products. That illustrated comprises cutting cylinders 72 to which the half speed web is run, these cylinders running, of course, at the speed of the web. The sheets are delivered to a transferring cylinder 74 which in turn delivers them to the full speed cutting and collecting cylinders 75, which are the cylinders which receive the web from the top or full speed deck. The sheets from the cylinder 74 are brought up to the speed of the sheets operated upon by the cylinders 75 during the transfer by a nipping roll indicated at 76. From the cylinders 75, the sheets pass over a folder of the longitudinal type, indicated at 77, and pass to any suitable delivery, not shown.

Collecting mechanisms of the type referred to are known in the art and a further specific description of the mechanism by which the various operations are carried out is, therefore, unnecessary. Reference may, however, be had to the patent to E. P. Sheldon, No. 572,225, dated December 1, 1896, for a full illustration and description of this type of mechanism.

It will be observed by making the top deck the full speed deck, the difficulties hereinbefore adverted to with relation to additional color cylinders are entirely obviated. There is plenty of room above the top deck for positioning such additional color cylinders as may be desired and the putting of such cylinders in place does not require any reconstruction of the machine. Thus, for instance, it will be readily understood that an additional color cylinder or cylinders can be added to the machine shown in Figs. 2 and 3 without any difficulty whatever. Further, the machine built in accordance with the invention may have its capacity increased by adding additional decks. The machine shown in Fig. 1, for instance, may be converted into the machine shown in Fig. 3, by simply adding a deck, which then becomes a full speed deck, suitable change gears being introduced to make the deck which was formerly a full speed deck a half speed deck. The machine shown in Fig. 1 is by proper manipulation of the collecting cylinders and proper control of the width of the web used on the half speed deck capacitated to produce all products varying by twos up to sixteen pages, except fourteen's.

The machine shown in Fig. 2 is capacitated to produce all products varying by twos up to twenty-four pages except twenty-two's. As illustrated, the machine is capacitated to produce fourteen pages by obtaining eight pages from the full speed deck, two pages from a half width web from the second deck which is run at half speed, and four pages from a full width web from the lower deck which is also run at half speed.

The machine shown in Fig. 3 is the same as that shown in Fig. 2, except that as arranged in this figure both the top and bottom decks are running at full speed and produce pages with which are united two page sheets cut from a half width half speed web running on the middle deck, and by running a full width web on this middle deck, twenty pages may be produced without change.

Changes and variations may be made in the construction by which the invention is carried into effect. The invention is not, therefore, to be limited to the particular construction hereinbefore described and shown.

What is claimed is:—

1. In a printing machine, the combination with a plurality of superposed decks of ro-

tary printing and perfecting couples, the cylinders of which are parallel and through which the webs are led in a straight line, of means for driving the top deck at full speed, the top deck being arranged to receive a color applying cylinder, means for driving a lower deck at varying speeds, including half speed, means for leading webs to and through the decks, means coöperating with said lower deck when it is driven at a slower speed than the top deck to bring its product up to the speed of the product of the top deck prior to its association therewith in order to obtain proper register, a collecting cylinder to which the product is led, and a folder to which the collecting cylinder delivers.

2. In a printing machine, the combination with a plurality of superposed decks of rotary printing and perfecting couples the cylinders of which are parallel and through which webs are led in a straight line, of a color applying cylinder forming a part of the top deck, means for driving the top deck at full speed, means for driving a lower deck at varying speeds, means for leading webs to and through the decks, means coöperating with said lower deck when it is driven at a slower speed than the top deck to bring its product up to the speed of the product of the top deck, a collecting cylinder to which the product is led, and a folder to which the collecting cylinder delivers.

3. In a printing machine, the combination with a plurality of superposed decks of rotary printing and perfecting couples the cylinders of which are parallel and through which webs are led in a straight line, the top deck being arranged to receive a color applying cylinder, of means including a train of gearing for driving the top deck at full speed, a shaft for operating the train, change gearing whereby said shaft may drive the lower deck at varying speeds, including half speed, means for leading webs to and through the decks, means coöperating with said lower deck when it is driven at a slower speed than the top deck to bring its product up to the speed of the product of the top deck prior to its association therewith in order to obtain proper register, a collecting cylinder to which the product is led, and a folder to which the collecting cylinder delivers.

4. In a printing machine, the combination with a plurality of superposed decks of rotary printing and perfecting couples the cylinders of which are parallel and through which webs are led in a straight line, of a color applying cylinder forming a part of the top deck, means including a train of gearing for driving the top deck at full speed, a shaft for operating the train, change gearing whereby said shaft may drive said lower deck at varying speeds, means for

leading webs to and through the decks, means coöperating with said lower deck when it is driven at a slower speed than the top deck to bring its product up to the speed of the product of the top deck, a collecting cylinder to which the product is led, and a folder to which said cylinder delivers.

In testimony whereof, I have hereunto set my hand, in the presence of two subscribing witnesses.

WILLIAM SPALKHAVER.
